UNITED STATES PATENT OFFICE

JOHN D. DAGGETT, OF SHAFER, MINNESOTA

DESIGN FOR A BIRD'S HOUSE

Application filed November 18, 1932. Serial No. 46,055. Term of patent 7 years.

To all whom it may concern:

Be it known that I, JOHN D. DAGGETT, a citizen of the United States, residing at Shafer, county of Chisago, and State of Minnesota, have invented a new, original, and ornamental Design for a Bird's House, of which the following is a specification, reference being had to the accompanying drawing, forming part thereof.

Figure 1 is a side elevation view of my new

and ornamental design for a bird's house.

Figure 2 is a top plan view of the same.

Figure 3 is a bottom plan view of the same.

Figure 4 is a cross-sectional view on the line 4—4 of Figure 2, of my new and ornamental design for a bird's house.

I claim:

The new and ornamental design for a bird's house substantially as shown and described.

JOHN D. DAGGETT.
